UNITED STATES PATENT OFFICE.

EDWARD ALBERT DAVIES AND STEPHEN THORPE THOMAS, OF WOLVERHAMPTON, ENGLAND, ASSIGNEES TO DAVIES BROTHERS & CO., LIMITED, OF SAME PLACE.

APPARATUS FOR REMOVING SCALE FROM SHEET METAL.

SPECIFICATION forming part of Letters Patent No. 591,621, dated October 12, 1897.

Application filed May 19, 1897. Serial No. 637,182. (No model.)

To all whom it may concern:

Be it known that we, EDWARD ALBERT DAVIES and STEPHEN THORPE THOMAS, subjects of the Queen of Great Britain, residing at Wolverhampton, in the county of Stafford, England, have invented certain new and useful Improvements in Apparatus for Use in Removing Scale which has been Raised on the Surfaces of Metal Sheets, of which the following is a specification.

This invention has for its object improvements in apparatus for use in detaching from the surfaces of metal sheets—such, for instance, as those which are intended to be galvanized or otherwise coated with metal or metallic alloy—scale which has been raised thereupon in any suitable scaling-furnace, and more especially the employment of such apparatus with a scaling-furnace such as that hereinafter described, through which the sheets are carried by means of endless chains. The scale is detached from the surfaces of the sheets, according to this invention, by means of apparatus which comprises a number of beaters, which as a sheet is traveling along with the under surface supported upon a plate or backing strike the upper surface thereof with great rapidity in such manner that nearly every portion of the upper surface of the sheet receives a sharp blow on its passage through the appliance. The scale is thus thoroughly loosened and detached from both surfaces of the sheet. Each sheet is drawn into the apparatus by means of a pair of feed-rolls and passes away therefrom through a pair of withdrawing-rolls, the blows being struck upon the upper surface of the sheet by a number of beaters arranged in position to strike upon the portion of the sheet which is passing the two pairs of rolls.

Figure 1 is a longitudinal section through a furnace such as it is preferred to use for raising the scale upon the surfaces of the sheets, and shows also the appliances by means of which the sheets are carried automatically into, through, and out from the furnace. Fig. 2 is a sectional plan of the furnace, and shows also, in plan view, the appliances for carrying the sheets therethrough. Fig. 3 is a transverse section through the fur-

nace, taken on line $x-x$ of Fig. 1. Fig. 4 is a section, to an enlarged scale, of one of the sprocket-wheels used with the endless chains which pass through the furnace, and shows also a side elevation of a portion of one of the chains. Fig. 5 is a plan of the wheel and length of chain shown by Fig. 4. Fig. 6 illustrates, in plan view, also to an enlarged scale, apparatus constructed according to this invention for the purpose of removing scale from the surfaces of metal sheets which has been previously raised thereupon in a suitable furnace. Fig. 7 is a longitudinal section taken on line $x'-x'$ of Fig. 6. Fig. 8 is a plan view of a modified form of the apparatus for detaching the scale from metal sheets. Fig. 9 is a longitudinal section taken on line $y-y$ of Fig. 8. Fig. 10 is a detached section, to an enlarged scale, of the frame carrying the beaters which are used in the modification shown by Figs. 8 and 9. Fig. 11 is a side elevation of a short length of such frame.

Referring first to Figs. 1 to 5, the furnace illustrated by such views is formed with a heating-chamber A for the sheets. This chamber is of a width to suit the maximum width of the sheets which are to be scaled therein and is of a length which is considerable compared with its width, being conveniently about thirty to thirty-five feet in length between the doors. Each end of the chamber A is normally closed by means of a door B, capable of being raised in vertical guides in the usual manner of raising similar doors, so as to completely open the ends. These doors, however, when closed do not completely close the ends of the chamber A, but leave a space at each end between the floor of the chamber A and the lower edge of the corresponding door through which the sheets are carried. The doors B do not appear in Fig. 2, as the section of such view is taken at a level immediately below the bottoms of the doors. Endless chains a pass around wheels b , which are in position some distance from the feeding-in end of the furnace, and around sprocket-wheels c , which are in position a short distance beyond the delivering end of the furnace, and these chains pass through the chamber A of the furnace and run upon

plates *d* upon the bottom of the chamber. The under sides of the chains run along metal channels *e*, which pass also through a hollow space *C*, formed underneath the chamber *A* 5 of the furnace. The spindle carrying the sprocket-wheel *c* is driven continuously from any suitable source of power, and the links of the chains are caused to move constantly through the chamber *A* in the direction of 10 the arrow *f*, Fig. 1. Each pair of side links of the endless chains *a* are formed with projections *a'*, (see Figs. 4 and 5,) upon which the sheets are placed for being carried into and through the chamber *A* by the movement 15 of the endless chains. The portions of the endless chains *a* which are at any time passing from the wheels *b* toward the furnace are carried by rollers *g*, which are capable of rotating in bearings supported by longitudinal 20 bearers *h*. The chains may be tightened from time to time, as the joints thereof wear, by screw-tightening devices *i*, which draw back along guides on their supporting-bed the bearings which support the spindle *j*, carrying the wheels *b*. Furnace-grates *D* are arranged along one side of the heating-chamber *A* and are provided with suitable joining doors *k*. The products of combustion from the furnace-grates *D* pass over the top of a 25 wall *l*, which divides them from the heating-chamber *A*, and thence into the heating-chamber, and pass away from such chamber through flues *m* at the bottom of the wall on the opposite side of such chamber, and thence 30 into a flue *E*, running along the side of the chamber, and thence through a flue *F* to the chimney. The chamber is maintained at a temperature which causes the sheets to be heated to a bright-red heat, and the scale is 35 thus raised on the surfaces of the sheets in a manner which adapts it to be readily removed by the apparatus hereinafter described. The doors *B* are normally down while the sheets are being carried into, through, and out from 40 the heating-chamber *A*, and are required only for obtaining access to the interior of the chamber for the purpose of repairs or in case of a sheet getting out of place during its passage therethrough. 45

50 Referring now to the apparatus shown by Figs. 6 and 7, *n n* are a pair of feeding-in rolls mounted in suitable bearings in the fixed framing *G* of the apparatus, and *o o* are a pair of corresponding withdrawing-rolls. 55 *p* is a fixed supporting-plate along which the sheets pass between the rolls *n n* and the rolls *o o*. *q* are a number of beaters, each formed conveniently of a flat section of bar shaped longitudinally, as shown. The beaters are 60 pivoted at their hinder ends to a round transverse bar *r*, which is fixed at each end to the framing of the machine. The beaters are arranged, as seen on plan, as near together side by side as will admit of their movement 65 independently of one another and are kept apart the required distance by washers *s* around the bar *r*, and as an additional pre-

caution are guided at their forward ends by guides *s'*, carried by a transverse bar *s*. The beaters are formed so that when down upon the sheet, as shown by full lines, Fig. 7, a considerable length of straight flat portion bears upon the surface of a sheet. The hinder end of each beater is bent up conveniently of a curved form to its pivot attachment with the bar *r* and is bent up at its forward end and terminates at such end in a short length of horizontal or horizontally-inclined portion *t*. *H* is a frame rigidly mounted upon a spindle *u*, which is capable of rotation in bearings carried by the framing of the machine. This frame consists, conveniently, of parts *v*, which are of the shape of band-pulleys and which are keyed upon the spindle *u*, and of longitudinal bars *w*, of angle-section, 85 which are fixed at intervals apart to the rims of the pulleys. As the frame is caused to rotate in the direction of the arrow *a'*, Fig. 7, the angle-bars *w* operate in succession to lift the forward ends of the beaters each into the 90 position indicated by broken lines, Fig. 7, and in passing out of contact with such ends allow the beaters to drop upon a sheet which is passing between the feeding-in and withdrawing rolls. The sheet is caused to travel 95 along the plate *p* at a velocity of about twenty feet per minute, and the frame *H* is caused to make about one hundred rotations per minute, and thus each beater of the row of beaters strikes a number of blows in rapid 100 succession upon the surface of the sheet with the result that the scale is dislodged from every part of the surface of the sheet. The action of the beaters upon the one side of the sheet dislodges the scale not only from such 105 side, but from the other side also, and renders it unnecessary to pass the sheets a second time through the apparatus.

The apparatus shown by Figs. 6 and 7 may be employed for treating sheets on the surface of which the scale has been raised in any suitable scaling-furnace, but it is preferred (and this is the more immediate purpose of the apparatus) to use such apparatus with a scaling-furnace such as that described with 115 reference to Figs. 1, 2, and 3. The line *b'*, Figs. 6 and 7, indicates the end of the furnace through which the sheets pass out to the apparatus for detaching the scale, and the sprocket-wheels *c* correspond to the wheels *c* 120 shown by Figs. 1 and 2. The chains which carry the sheets through the furnace of course travel at the same speed as the surface velocity of the rolls *n n* and *o o*. The sheets are delivered by the endless chains 125 onto guides *c'* and between the rolls *n n*. The forward ends of the sheets are guided between the rolls *n n* by means of the guides *c'* and a slanting plate *d'*. The pairs of rolls *n n* and *o o* may be driven in any convenient manner. 130 In Fig. 6 the pair *o o* are shown to be driven by means of a chain from one of the rolls *n*, and the rolls *n* are shown to be driven through the medium of a shaft *e'*, from which the

sprocket-wheels c are also driven. The shaft e is provided with fast and loose pulleys f' , so that it may be readily stopped and started, and a hand-wheel g' is fixed upon one end of such shaft, so that it may be turned back by hand to reverse the rolls $n n$ in case a sheet enters improperly between the rolls. The spindle u , carrying the rotating frame H , is driven independently of the rolls $n n$ and $o o$, so that it may be caused to rotate only while a sheet is passing beneath the beaters, and the unnecessary wear and tear be thus avoided which would result from allowing the beaters to strike upon the backing-plate p all the time that the rolls were rotating while a sheet was not passing beneath the beaters. As the work comes somewhat suddenly upon the rotating frame each time the set of beaters is raised, it is preferred to drive such frame through the medium of a pinion h' on the band-pulley shaft and a wheel i' on the spindle of the rotating frame rather than to drive with a band passing around a pulley fixed upon the spindle of the rotating frame. The portions $k' k'$ of the rolls which are between the ends of the operative surfaces thereof and the necks are reduced somewhat in diameter to prevent scale from the sheets creeping along the rolls into the necks. Two or more sets of beaters may be employed in the treatment, as above described, of each sheet upon which the scale has been raised in the special form of sealing-furnace above described or other sealing-furnace, but such will not be found necessary.

The apparatus shown by Figs. 8 to 11 differs from that already described with reference to Figs. 6 and 7 only in respect of the beaters and the method of mounting and operating them. In this case a number of wings or beaters l' , each formed conveniently of a flat section of steel curved somewhat longitudinally, as shown, are hinged or pivoted to the rotating frame H . The beaters are conveniently arranged in rows lengthwise of the frame, the beaters of one row being placed, preferably, to break joint with those of the adjacent row on each side, as clearly shown by Figs. 8 and 11. The frame H , carrying the beaters, is driven to rotate in the direction indicated by the arrow m' , Fig. 9, and the beaters are hinged to the frame in such manner that as the frame rotates they fly out and strike with considerable force upon the surface of a sheet which is passing between the rolls $n n$ and rolls $o o$. The beater lettered l^2 of Fig. 10 is shown to be in position in which it would be when upon the surface

of a sheet passing between the pairs of rolls. After a beater has struck the sheet it is 60 dragged forward thereupon until it is lifted clear again by the rotation of the frame H . The beaters are curved outwardly, as shown, so that their convex surfaces strike upon the surface of a sheet, and the purpose of forming them of a curved shape longitudinally is to prevent their outer ends striking and indenting the sheet. Plain longitudinal bars n' are fixed parallel to the spindle u at equal distances apart around the rims of the parts 70 v of the rotating frame. The beaters l' are pivoted to lugs o' , which are fixed to the bars n' . Bars p' , also running parallel with the axis of the spindle u , are fixed to the rims of the parts v for the purpose of preventing any 75 beaters which are at the upper side of the rotating frame, when such frame is at rest or moving slowly, from falling too much inward. As in this modification the work of the rotating frame is tolerably regular, such frame may 80 be driven by means of a band passing around a pulley on the spindle of such frame.

What we claim as our invention, and desire to secure by Letters Patent, is—

1. Apparatus for use in detaching, from the 85 surfaces of metal sheets, scale which has been raised thereupon in a suitable furnace, which comprises a backing or support for the sheets, means for traversing the sheets along the backing or support, beaters arranged in position over the backing or support, and mechanism for operating the beaters, all substantially as described and shown.

2. Apparatus for use in detaching, from the 95 surfaces of metal sheets, scale which has been raised thereupon in a suitable furnace, which comprises a backing-plate or support for the sheets, a pair of feeding-in rolls, a pair of withdrawing-rolls, beaters arranged over the backing-plate or support, and a rotating appliance 100 for operating the beaters, all substantially as described and shown.

3. The combination of the backing-plate or support p , feeding-in rolls $n n$, withdrawing-rolls $o o$, beaters q , rotating frame H having lifters w , substantially as described and shown, for the purpose set forth.

In witness whereof we have hereunto signed our names in the presence of two subscribing witnesses.

EDWARD ALBERT DAVIES.
STEPHEN THORPE THOMAS.
